Attorney.

UNITED STATES PATENT OFFICE.

ALEXANDER IZEN, OF ST. LOUIS, MISSOURI, ASSIGNOR TO SMITH & DAVIS MFG. CO.,
OF ST. LOUIS, MISSOURI, A CORPORATION OF MISSOURI.

CRIB.

1,423,663.

Specification of Letters Patent. Patented July 25, 1922.

Application filed July 15, 1921. Serial No. 484,965.

To all whom it may concern:

Be it known that I, ALEXANDER IZEN, a former subject of the former Czar of Russia, who have declared my intention of becoming a citizen of the United States, residing at St. Louis, State of Missouri, have invented certain new and useful Improvements in Cribs, of which the following is a specification.

10 My invention has relation to improvements in corner-pieces for bed-bottoms and is more particularly directed to the corner-pieces whereby the bottoms of cribs are secured to the posts at the head and foot of the 15 crib.

The object of the present invention is to provide a corner-piece that shall engage a suitable projection on the bed posts whereby the bed-bottom from which the corner-piece 20 projects may be securely fastened to the posts. In view of the fact that cribs are entirely enclosed by end and side members it is necessary to support the crib-bottom on the corner posts in a manner that the bottom 25 will be clear of these members. In other words, the outer boundaries of the bed-bottom lie wholly within the end and side members of the crib. A further object is to provide corner-pieces for cribs that are simple 30 and that will permit of quickly assembling the crib.

Further and other advantages will be apparent from a detailed description of the invention in connection with the accompanying drawings, in which—

Figure 1 is a plan view of the crib, showing the crib-bottom provided with my improved corner-pieces; Fig. 2 is a side elevation of the same; Fig. 3 is an enlarged plan 40 view of one corner of the crib-bottom with my invention applied thereto; and Fig. 4 is a horizontal cross-section on the line 4—4 of Fig. 3.

Referring to the drawings, A, A represent 45 the end members of the crib of which the posts 1, 1 form a part, and B and B' represent the side members, the side member B' being capable of dropping downwardly to permit ready access to the crib. This sliding 50 side member is old and the mechanism thereof need not be described in detail although obviously to permit of this movement the crib-bottom C must come entirely within the plane of movement of the side member. A

pin 2 is secured in each post at the height determined for the crib-bottom, said pin traversing the post and projecting a short distance beyond the inside thereof, the outer end of the pin being reduced so as to form a shoulder a, against which the inside surface 60 of the post wall bears, the pin being riveted against the post opposite the shoulder a, thereby securely fastening the pin in the post.

The crib-bottom comprises a pair of angle 65 iron end members 3, 3 and angle iron side members 4, 4 the horizontal legs of the angles being lapped at the corners and riveted together, and a link fabric 5 stretched between the side and end members.

On each corner of the crib-bottom C is secured my improved corner, the same comprising two members 6 and 7 of flat metal each bent substantially L-shaped, the legs of the L, however, being connected by an inclined portion. The two members are now riveted (or otherwise secured) together at the inclined portions so that the legs form a right angle on both sides of the juncture or neck b, i. e., the corner is bifurcated on both sides of the neck. The legs c and d of the inner fork are adapted to receive the corner of the bed-bottom C and are riveted to the angle iron end rails and side rails 3 and 4 respectively. The outer fork is adapted to 85 embrace the corner-post 1, and the leg c' of the member 6 is provided with an inclined slot m which is slipped over the pin 2 projecting from the post. As the slot m moves down over the pin 2, the leg c' will be drawn in the direction of the arrow a and the leg d' will be drawn tightly against the post 1 thereby causing the corner to be wedged tightly against the post. Obviously when all four corners of the crib-bottom are thus 90 secured to the posts 1 a very secure connection is had between the crib ends and sides with the bottom, and at the same time the bottom may be readily removed by forcing the corners upwardly from the pins 2.

Having described my invention, I claim:

In combination with a bed having end members provided with posts, pins projecting inwardly from said posts, a bed-bottom having corner-pieces projecting outwardly therefrom at an angle of substantially forty-five degrees, said corner-pieces comprising two metallic members bent substantially L-

shaped, the legs of each L being connected by a neck, said L-shaped members being secured together at their necks so as to provide oppositely disposed forks, one of said 5 forks engaging the corner of the bed-bottom and secured thereto, the other being adapted to embrace a bed-post, and one side of the

last mentioned fork being provided with an inclined slot for receiving one of the afore-said pins for supporting the bed-bottom. 10

In testimony whereof I hereunto affix my signature.

ALEXANDER IZEN.
